PUMPING SYSTEM FOR COLD LIQUIDS

Elmer S. Messer, Tulsa, Okla., assignor to Conch International Methane Limited, Nassau, Bahamas, a corporation of the Bahamas

Filed Jan. 23, 1961, Ser. No. 34,216
10 Claims. (Cl. 222—333)

This invention relates to a deep well pump for the removal of liquid from a tank and it relates more particularly to a pumping system for use in the displacement of an extremely cold liquid from a deep tank of large capacity.

The problems sought to be overcome by this invention arose in the removal of liquefied natural gas from a tank of large capacity in which it was stored. Thus the invention will be described hereinafter with reference thereto but it will be understood that similar problems will exist in the removal of any extremely cold liquid from a tank of large capacity.

Liquefied natural gas is a liquid which is composed mostly of methane and thus has a boiling point at atmospheric pressure which may range from about —240° F. to about —258° F., depending upon the amount of heavier hydrocarbons present. Attempts have been made to store and transport the liquefied gas in large tanks either in land storage or in ship transportation. For the removal of the liquid, a displacement pump was provided in the bottom of the tank for operation by a shaft extending through an elongate cylindrical housing which reaches from the pump to the top of the tank and through the cover on which the power operating means was located.

This arrangement encountered numerous difficulties in practice because of the camber of the cylindrical housing or distortion of the elongate shaft either in response to load in operation or because of the non-uniform expansion and contraction characteristics between the closely fitting elements during the wide changes in temperature from ambient temperature when the tank is empty to about —258° F. when the tank is filled with liquid cargo. Another problem which has been encountered is the effect of the extreme cold in freezing the shaft tight such that operation could not be effected when it was desired to remove the liquid. When such interference or failures occur, repairs cannot be made to return the elements to operating condition without removal of substantially the entire quantity of liquid from the storage tank by means other than the incapacitated pump.

It is, therefore, an object of this invention to provide a pumping means for the removal of cold liquids from a tank of large capacity and it is a related object to provide a removal means of the type described which is simple in construction and easy in operation; which is capable of removal or repair without the necessity for the displacement of the liquid from the container, and which is not subject to failures of pumping systems of the type heretofore described.

These and other objects and advantages of this invention will hereinafter appear and for purposes of illustration, but not of limitation, embodiments of the invention are shown in the accompanying drawings in which—

FIG. 1 is a schematic sectional elevational view of a liquid storage tank embodying the features of this invention;

FIG. 2 is an enlarged sectional elevational view of the pumping means embodied within the tank of FIG. 1;

FIG. 3 is a sectional view similar to that of FIG. 2 showing the elements in the pumping means as arranged during withdrawal of the displacement pump;

FIG. 4 is a sectional elevational view similar to that of FIG. 2 showing a modification in the construction of the pumping means, and

2

FIG. 5 is a sectional view similar to that of FIG. 3.

Referring now to the drawings, the numeral 10 represents a storage tank of large capacity for housing cold liquid 12, such as liquefied natural gas. It will usually be enclosed within a relatively thick layer 14 of thermally insulating material or, when mounted within the hold space of a ship, for the water transportation of the liquefied natural gas, the hold may be lined with thermally insulating material to provide a hold space in which one or more tanks may be mounted. The tank will be provided also with the usual inlet pipe 16 for the introduction of the cargo liquid into the tank and an outlet pipe 18 for removal of liquid cargo from the tank. In addition, a vent 20, fitted with a pressure relief valve 22, will be arranged to communicate through the top wall of the tank with the vapor space 24 to prevent the build-up of pressures within the tank.

In the modification illustrated in FIGS. 1-3, the removal means is confined within an outer housing 25 of relatively small cross-section and which extends vertically through the height of the tank from the bottom wall 26 to the top wall 28 with the periphery of the housing being secured in sealing relation to the respective top and bottom walls, as by welding 30 to form an integral part thereof. The housing, preferably in the form of a cylindrical or tubular casing, is formed of a fluid and vapor impervious, temperature-insensitive material, such as aluminum or alloys of aluminum, stainless or other high nickel steels and the like metals which do not lose much of their ductility or strength at temperatures below —100° F.

Telescoped within the outer housing is an inner housing 32 dimensioned to have an outer wall to wall dimension slightly less than the inner wall to wall dimension of the outer housing to provide a narrow annular space 34 in between. The inner housing 32 is free of the outer housing to enable relative movement in the vertical direction for displacement of the inner housing into and out of the outer housing. A cover plate 36 spans the open end of the inner housing and the opening 38 in the tank with the overhang 39 of the cover being secured, as by means of hold down bolts 40, to the top wall of the tank to seal off the openings. The cover plate 36 can be joined to the upper end of the inner housing to form a part thereof or it may be arranged merely to engage the upper end of the inner housing in sealing relationship, when in position of use.

The liquid removal means is mounted within the lower end portion of the inner housing 32 and it is attached thereto for movement into and out of the tank with the housing. Such liquid removal means includes a pump 42 having an inlet 43 on the underside and an outlet 44. The pump is supported from the underside of a bracket plate 46 which extends crosswise of the inner housing in the lower end portion thereof to separate the pump section 47 from the remainder. An elbow 48 connects the outlet 44 with an opening in the plate through which the liquid is transmitted from the pump to an outlet pipe 50 which extends vertically through the remainder of the inner housing and through an opening 51 in the cover to the exterior of the tank for connection to the delivery pipe 18.

The pump is operated by a driving means represented by an electrical motor 52 mounted on the top side of the bracket plate 46 with a driving shaft extending therethrough to the pump. It will be understood that the driving means may be in the form of a motor or turbine powered by a fluid, gas or liquid.

Liquid is admitted to the pumping space in the lower end portion of the housing for removal from the tank by passage from the tank into the housing through openings 54 in the lower end portion of the housing. The openings are in communication with one or more open-

ings 56 through the lower portion of the outer housing either through the annular space 34 or else by arrangement of the openings 54 and 56 in substantial crosswise alignment. It is desirable to screen the liquid to militate against solid matter entering the pump. For this purpose, the pump inlet can be covered with a screening member but it is preferred to make use of such screening member 58 across the openings 54 through the inner housing.

It is desirable also to be able to stop the flow of liquid through the openings in the outer cylindrical housing 25 when the inner cylinder is raised from its position of use thereby to enable most of the liquid to be displaced from within the outer cylinder by the pump before the complete removal of the inner housing. One such means operative automatically to shut off flow responsive to displacement of the inner housing from its position of use on the bottom of the tank and to renew the flow in response to movement of the inner housing to its lowered position of use is shown schematically in FIGS. 2 and 3. It will be understood that other similar means for releasably blocking the opening or openings may be employed.

In the modification shown, each of the openings 56 through the outer housing 25 is provided with an enclosure 60 having a passage 62 in communication with the opening 56. A check valve in the form of a gate 64 is mounted within the enclosure for rocking movement about its pivot 66 between a lowered or blocking position sealing the passage to prevent the flow of liquid therethrough and an open or unblocked position which frees the passage for the flow of liquid therethrough. Rocking movement of the gate between blocking and unblocking positions can be controlled through a link 68 connected to the gate at the pivot and extending through an opening 56 in the outer housing into the path of an abutment 70 on the inner housing in position to rock the link to lowered position for unblocking the gate when the inner housing nears its position of use and to release the link 68 to enable the gate gravitationally to rock to blocking position responsive to movement of the inner housing from its lowered position of use.

When the gate is closed, the pump can be operated, if desired, though it is not necessary, to remove the liquid from within the inner housing to the level of the inlet to the pump. This will leave but a small amount of liquid within the outer housing so that no interferences or difficulties will be experienced in either the removal or the return of the pump section. To assist in guiding and in stabilizing the position of the inner housing 32 within the outer housing 25, sealing or guide members 72 can be provided therebetween in vertically spaced apart relation and preferably in the upper and the lower portions, as shown.

In the modification shown in FIGS. 4 and 5, use is made only of the equivalent of the inner housing formed of vertically disposed walls 80, a bottom wall 82 and a cover plate 84 the latter of which is adapted to be secured in sealing relationship across the opening 86 in the top wall 28 of the tank by the use of hold-down bolts 88 securing the over-hanging portion of the cover plate to the underlying portion of the top wall 28 of the tank, preferably with a sealing gasket 90 in between. The bottom wall 82 of the housing can be removably secured to the bottom wall 26 of the tank to enable removal of the entire inner housing.

The pump 92 is illustrated as a hydraulic pump having an inlet to the pump chamber in the bottom and separated from a base 94 on which it is supported by a grating 96 through which the liquid is strained before being sucked into the pump housing for delivery to the passage 98 through which the liquid is raised to the surface and through the cover 84 to the header 18. The driving means can be a submerged electrical motor, as in the former modification, but illustration is made here of an alternative use of a hydraulic motor 100 adapted to be

operated by a fluid, such as Freon or other liquid gas or fluid having a solidification or freezing point temperature below the temperature of the liquid. When a hydraulic motor is employed a passage 102 is provided for transmission of the driving fluid to the inlet 104 of the motor 100 and another passage 106 is provided for return of the fluid from the outlet 108 to a supply source outside of the tank. When the passages 98, 102 and 106 are formed of a material differing from the housing or the tank, expansion and contraction means should be incorporated, such as the bellows sections 110 at the upper end portions of each of the passages. The motor is supported from the pump on a pedestal 112 and it is operatively connected thereto by means of a drive shaft 114. When bellows are employed as an expansion means, it is desirable to provide a stop 116 to limit the amount of expansion capable of taking place.

In the described modification, the motor 100, pump 92, and passages 98, 102 and 106 can be removed independently of the housing. It is desirable to provide means for releasably anchoring the pump and motor in a stabilized position within the housing and also to militate against undesirable camber during movement of the carrier or ship. For this purpose, the base 94, on which the pump is supported, is formed to polygonal shape, such as rectangular, with the edges 118 cammed downwardly.

Aligned with the cam edges 118 of the base member 94 are blocks 120 and 122 fixed to the bottom wall of the housing with the inner edges 124 downwardly and outwardly inclined to receive the cam edges 118 of the base member in fitting relationship thereunder. For release of the base to enable removal of the pump and motor assembly, two of the adjacent blocks 122 are formed with end portions 122^a which are shiftable between an extended position in which the cam surfaces are in abutting relationship for anchorage of the base member and a retracted position in which the cam surfaces are separated by an amount to enable the base member to be released for vertical displacement. Release from the stationary blocks 120 is assisted by pusher rods shiftable through an opening in the end wall of the blocks between an extended position and retracted position and in which the rods are constantly urged toward the extended position by resilient means, such as springs in the base of the opening.

To guide the base member into proper position between the blocks, the housing is provided with downwardly inclined guide plates 128 in which the lower end portions terminate in vertical alignment with the proper position of the engaged edge portion of the base member. The end portion 122^a of the blocks 122 are displaced between blocking and unblocking position by means of piston rods 130 secured at their outer ends to the blocks 122 and extending from a piston 132 shiftable within a cylinder 134 having an inlet at one end and an outlet at the other for the transmission of hydraulic fluids through lines 136 and 138 for actuating the piston.

The housing is provided with one or more ports 140 in the lower end portion thereof for the flow of liquid from the tank into the housing and pump. The ports are adapted to be closed by a plug 142 shiftable vertically into and out of port closing position, as by means of a hydraulic piston 144 and cylinder means 146 having the plug 142 on the end of the rod for displacement therewith. The cylinder is supplied with hydraulic fluid through lines 148 and 150 which are in communication with the inlet and outlet of the piston-cylinder assembly.

It will be understood that the blocking member 142 may be mounted for movement in directions other than vertically into and out of blocking position and that such movements may be effected by means other than the hydraulic piston and cylinder assembly. The flow lines 136, 138, 148 and 150 to the operating cylinders extend through the housing for communication with the supply source of pressure fluid for actuation.

Where, as in the first modification, the driving means comprises an electrical motor 52, the inner housing can be dimensioned to be smaller in cross-section, such as from 18 to 36 inches. When the driving motor is in the form of a hydraulic motor 100 which requires additional passages 102 and 106 for the transmission of driving fluid, then a housing of larger cross-section will be desired. In the latter instance, it is advantageous to make use of guides 152 in vertically spaced apart portions of the housing for stabilizing the positions of the passages.

It will be apparent from the foregoing description that I have provided a simple and sturdy construction which stabilizes the position of removal means to prevent undesirable camber of the operating elements responsive to the pitching and rolling movements of the ship or other carrier means. I have provided a submerged pump having a drive which is not subject to binding or freezing which otherwise might prevent operation thereof. Most important, I have provided a means for easy access to the pump and motor assembly for replacement or repair or for complete removal of the entire pump housing and drive without the necessity first to remove the liquid from the tank. When it is desired to effect removal of liquid from the interior housing for removal of a pump which has failed or for other reason when the pump is inactive, auxiliary means can be provided for liquid removal. One such means, illustrated in broken lines in FIG. 4, comprises an inlet 200 through the cover, having a connection with a source of nitrogen under pressure. A drain line 202, provided with a check valve 204, extends from an intermediate portion of the discharge line 98 to the bottom portion of the interior housing for displacement of liquid from within the housing through the drain line 202 to the discharge line 98 in response to pressure maintained within the inner housing by the admission of nitrogen.

It will be understood that changes may be made in the details of the construction, arrangement and operation without departing from the spirit of the invention, especially as defined in the following claims.

I claim:

1. Means for the removal of a cold liquid from a deep well tank comprising an outer enclosure extending lengthwise through the tank; an inner enclosure concentric with said outer enclosure and spaced a short distance therefrom, said inner enclosure being shiftable vertically within said outer enclosure through the top of the tank between lowered and raised positions; pump means having an inlet and an outlet, said pump means being mounted in the lower end portion of the inner enclosure for submergence below the level of the tank when filled; a motor mounted in the lower end portion of the inner enclosure adjacent the pump means and operatively connected thereto for operation of the pump means; means communicating the outlet of the pump means with the exterior of the tank for delivery of liquid displaced by the pump means; a passage in the lower end portion of the inner enclosure through which liquid can flow from the tank into said enclosure to the inlet of the pump means, said outer enclosure secured at opposite ends in sealing relationship to the adjacent top and bottom walls of the tank to form an integral part thereof, a port in the outer enclosure adjacent the lower end thereof for communicating the interior of the outer enclosure with the interior of the tank, means for opening and closing said port.

2. Means as claimed in claim 1 which includes guides between the enclosures properly to align the concentric enclosures with a spaced relationship therebetween.

3. Means for the removal of a cold liquid from a deep well tank comprising an enclosure extending lengthwise through the tank and shiftable vertically through the top of the tank between lowered and raised positions; pump means mounted in the lower end portion of the enclosure for submergence below the level of the tank when filled; a motor mounted in the lower end portion of the enclo-

sure adjacent the pump means and operatively connected thereto for operation of the pump means; means communicating the outlet of the pump means with the exterior of the tank for delivery of liquid displaced by the

5 pump means; a passage in the lower end portion of the enclosure through which liquid can flow from the tank into the enclosure and to the pump means; means selectively opening and closing the passage to control the flow of liquid from the tank into the enclosure, and a partitioning bracket fixed to extend crosswise of the enclosure in the lower end portion thereof and to which the pump means and the driving means are secured in mounted relation.

10 4. Means as claimed in claim 3 in which the pump means is secured to the underside of the bracket and the motor is mounted on the top side of the bracket above the pump means.

15 5. Means as claimed in claim 1 in which the passage communicating the tank with the first mentioned enclosure comprises an opening through the first mentioned enclosure in the lower end portion thereof, an opening in the outer enclosure at a level corresponding to the opening in the first mentioned enclosure.

20 6. Means as claimed in claim 5 in which the means selectively opening and closing the passage comprises a gate shiftable toward and away from the opening in the outer enclosure between blocking and unblocking positions.

25 7. Means as claimed in claim 6 which includes means operatively connected to the gate for automatic displacement between blocking and unblocking positions responsive to displacement of the first mentioned enclosure away from and toward lowered position respectively.

30 8. Means as claimed in claim 7 in which the gate is pivoted for rocking movement between blocking and unblocking position, an abutment on the first mentioned enclosure, a link operatively connected to the gate and having a portion in the path of the abutment whereby the link is displaced to rock the gate to unblocking position responsive to movement of the first mentioned enclosure to lowered position and whereby the link is released to enable the gate to rock to blocking position responsive to displacement of the first mentioned enclosure from lowered position.

35 9. Means for the removal of a cold liquid from a deep well tank comprising an enclosure extending lengthwise through the tank and shiftable vertically through the top of the tank between lowered and raised positions; pump means mounted in the lower end portion of the enclosure

40 for submergence below the level of the tank when filled; a motor mounted in the lower end portion of the enclosure adjacent the pump means and operatively connected thereto for operation of the pump means; means communicating the outlet of the pump means with the exterior of the tank for delivery of liquid displaced by the pump means; a passage in the lower end portion of the enclosure through which liquid can flow from the tank into the enclosure and to the pump means; means selectively opening and closing the passage to control the flow of liquid from the tank into the enclosure; the pump means and the motor being removably secured in the lower end portion of the enclosure for separation therefrom; a pump base upon which the pump means is mounted and which includes means for releasably engaging said base for releasably holding said pump means within the enclosure; said base comprising a polygonal member in cross-section having cam edges, cam plates fixed to the enclosure at least some of which are shiftable toward and away from the cam edges of the base member releasably to lock the base member to the enclosure.

45 10. Means for the removal of a cold liquid from a deep well tank comprising an enclosure extending lengthwise through the tank and shiftable vertically through the top of the tank between lowered and raised positions; pump means mounted in the lower end portion of the enclosure

50 for submergence below the level of the tank when filled; a motor mounted in the lower end portion of the enclosure adjacent the pump means and operatively connected thereto for operation of the pump means; means communicating the outlet of the pump means with the exterior of the tank for delivery of liquid displaced by the pump means; a passage in the lower end portion of the enclosure through which liquid can flow from the tank into the enclosure and to the pump means; means selectively opening and closing the passage to control the flow of liquid from the tank into the enclosure; the pump means and the motor being removably secured in the lower end portion of the enclosure for separation therefrom; a pump base upon which the pump means is mounted and which includes means for releasably engaging said base for releasably holding said pump means within the enclosure; said base comprising a polygonal member in cross-section having cam edges, cam plates fixed to the enclosure at least some of which are shiftable toward and away from the cam edges of the base member releasably to lock the base member to the enclosure.

55 11. Means for the removal of a cold liquid from a deep well tank comprising an enclosure extending lengthwise through the tank and shiftable vertically through the top of the tank between lowered and raised positions; pump means mounted in the lower end portion of the enclosure

60 for submergence below the level of the tank when filled; a motor mounted in the lower end portion of the enclosure adjacent the pump means and operatively connected thereto for operation of the pump means; means communicating the outlet of the pump means with the exterior of the tank for delivery of liquid displaced by the pump means; a passage in the lower end portion of the enclosure through which liquid can flow from the tank into the enclosure and to the pump means; means selectively opening and closing the passage to control the flow of liquid from the tank into the enclosure; the pump means and the motor being removably secured in the lower end portion of the enclosure for separation therefrom; a pump base upon which the pump means is mounted and which includes means for releasably engaging said base for releasably holding said pump means within the enclosure; said base comprising a polygonal member in cross-section having cam edges, cam plates fixed to the enclosure at least some of which are shiftable toward and away from the cam edges of the base member releasably to lock the base member to the enclosure.

65 12. Means for the removal of a cold liquid from a deep well tank comprising an enclosure extending lengthwise through the tank and shiftable vertically through the top of the tank between lowered and raised positions; pump means mounted in the lower end portion of the enclosure

70 for submergence below the level of the tank when filled; a motor mounted in the lower end portion of the enclosure adjacent the pump means and operatively connected thereto for operation of the pump means; means communicating the outlet of the pump means with the exterior of the tank for delivery of liquid displaced by the pump means; a passage in the lower end portion of the enclosure through which liquid can flow from the tank into the enclosure and to the pump means; means selectively opening and closing the passage to control the flow of liquid from the tank into the enclosure; the pump means and the motor being removably secured in the lower end portion of the enclosure for separation therefrom; a pump base upon which the pump means is mounted and which includes means for releasably engaging said base for releasably holding said pump means within the enclosure; said base comprising a polygonal member in cross-section having cam edges, cam plates fixed to the enclosure at least some of which are shiftable toward and away from the cam edges of the base member releasably to lock the base member to the enclosure.

75 13. Means for the removal of a cold liquid from a deep well tank comprising an enclosure extending lengthwise through the tank and shiftable vertically through the top of the tank between lowered and raised positions; pump means mounted in the lower end portion of the enclosure

enclosure for submergence below the level of the tank when filled; a motor mounted in the lower end portion of the enclosure adjacent the pump means and operatively connected thereto for operation of the pump means; means communicating the outlet of the pump means with the exterior of the tank for delivery of liquid displaced by the pump means; a passage in the lower end portion of the enclosure through which liquid can flow from the tank into the enclosure and to the pump means; means selectively opening and closing the passage to control the flow of liquid from the tank into the enclosure; the pump means and the motor being removably secured in the lower end portion of the enclosure for separation therefrom; guide means within the lower end portion of the enclosure for guiding the pump means to a position in vertical alignment with its lowered position during displacement of the pump means into the enclosure toward

its lowered position, said guide means comprising guide plates extending inwardly and downwardly from the sides of the inner enclosure and terminating in vertical alignment with the outer edges of the pump base when in lowered position.
